FLEXIBLE CLOSURE DEVICE
 Morton Jeskin, 16 Cold Spring Hill Road,
 Huntington, N.Y.
 Filed Mar. 9, 1959, Ser. No. 797,946
 1 Claim. (Cl. 160—201)

The present invention relates to flexible closure devices, such as doors, covers, shutters and the like structures, more particularly to closure devices of the type comprising a set of adjoining slats projecting into and having their ends slidably supported in the grooves or channels of a pair of guide members or supports and being pivotally connected with each other, to allow of sliding movement within said grooves or guides comprising both straight and curved portions or sections.

In the known rolling or sliding type of closure devices of the above type, the slats must first be connected or assembled, to form a flexible or articulated structure or assembly which is then inserted into the guide grooves or channels of the supporting device, to serve as a door, cover, shutter or the like closure device or unit. Aside from the added cost of the assembly operations and the requirement of special connecting means of the slats, the usefulness and mechanical strength of such devices is no greater than that of a single element or slat, as well as of the connecting means therebetween, whereby to render it necessary in case of damage or failure, to disassemble the entire device for the replacement of defective parts or elements and/or for the carrying out of repairs or adjustments. This applies both to arrangements of the type wherein the adjoining slats are joined together by means of separate connecting means, as well as to structures of the type wherein all the slats are connected by means of a common supporting member, such as in the form of one or more canvas or the like flexible webs being glued or otherwise secured to or within the slats, to pivotally connect the same and to form a unitary flexible or articulated structure or assembly, in the manner well known in the art.

Accordingly, a principal object of the present invention is the provision of a flexible closure device of the above type comprising a set of adjoining slats frictionally and pivotally engaging each other and slideable within the grooves of a pair of guide members or supports, whereby any separate connecting means between adjacent slats are dispensed with and the device may be assembled and disassembled readily and expeditiously by simply feeding or inserting the slats into and withdrawing the same from the grooves or channels of the guiding members or support.

Another object of the invention is the provision of a flexible closure device of the above type which, while providing a tight and close structure, is capable of sufficient flexing in at least one direction, to allow its being readily slid or passed around sharp curves or corners of the guide channels or sideways in the supporting device.

Yet another object of the invention is the provision of a flexible closure device of the above type which is both simple in design and inexpensive to manufacture and which can be assembled and disassembled readily and expeditiously without the use of special tools or skilled labor.

The invention, both as to its ancillary objects and novel aspects, will be better understood from the following detailed description, taken in reference to the accompanying drawing forming part of this specification and illustrating a preferred embodiment of the invention.

In the drawing, in which like reference characters denote like parts in the separate views, thereof.

FIG. 1 is a cross-section showing the construction of

2

a single constructional element or slat of the improved flexible closure device according to the invention;

FIG. 2 is a cross-section taken on line 2—2 of FIG. 3 and showing a complete closure unit or device comprising a set of slats according to FIG. 1 and a cooperating guide or supporting device constructed in accordance with the invention, and

FIG. 3 shows, on a reduced scale, a top or side view of a closure device or unit of the type according to FIG. 2.

Referring more particularly to FIG. 1, the constructional element shown consists essentially of a flat element or slat 10 of rectangular cross-section having a thickness D and being made of any suitable material, such as wood, synthetic plastic or the like moldable or easily workable material. Provided at the opposite ends of the element 10 are a pair of grooves or depressions 11a and 11b extending substantially transverse to and from the opposite faces 15a and 15b of the element, in such a manner as to provide a pair of claw-shaped locking or end portions 12a and 12b respectively, of reduced height, as shown at 13a and 13b, and adapted to mutually interlock with and to pivotally engage the grooves of the adjacent slats or elements in the assembled position, to thereby provide a flexible closure unit in cooperation with a pair of suitable guides or supporting members as will be described in greater detail hereafter.

Preferably, the grooves 11a and 11b have a depth *d* being equal to the height *h* of the claw portions 12a and 12b and extending beyond the longitudinal cross-sectional median line *a—a* of the slats, as shown in the drawing. In other words, the height of the claw portions 12a and 12b, or of the inner edges 13a and 13b, also extends beyond the line *a—a*, whereby to provide a substantially flat structure in the assembled position of the slats, as will become further apparent from the following. Furthermore, the width *w* at the grooves or depressions 11a and 11b is equal to the width of the claw portions 12a and 12b, to ensure a close fitting structure or assembly.

The inner edge 14a of one of the grooves, that is groove 11a in the example shown, and the outer edge 14b of the claw portion, at the opposite end of the slat, that is, the claw portion 12b in the example shown, are slightly slanting towards the transverse cross-sectional median line *b—b* of the slats by an angle α being of the order of about 10° to 15° and depending upon the degree of curvature of the guide grooves of the support or guiding members for the slats in the assembled position, whereby to provide coordinated pairs of substantially straight grooves and end portions 11b and 12a, on the one hand, and slanting grooves and end portions 11a and 12b, on the other hand.

FIGS. 2 and 3 illustrate the assembled closure device or unit comprising a plurality of slats 10 constructed in the manner according to FIG. 1 and held in assembled position by means of a pair of suitable guide members or supports 15a and 16b with the straight claw portions 12a of one slat engaging the straight grooves 11b of the adjacent slat of the set and with the slanting edges 14a and 14b adjoining one another, as at *y*, in such a manner as to cause a firm inter-engagement of the adjacent slats and to prevent pivotal movement or relative flexing of the slats in one direction, that is, in the upward direction in the example shown, by virtue of the close interlock

of the claw portions 12a with the grooves 11b, as shown at *x* in the drawing.

At the same time, the assembly allows of sufficient relative flexing or pivotal movement of the adjacent slats in the opposite, that is, the downward direction in the example shown, by virtue of the free spaces *y* between the adjoining slanting edges 14a and 14b. As a consequence, the width *W* of the guide members 15a and 15b

may be held to a minimum in relation to the thickness D of the slats 10, thus affording a tight and close fit between adjacent slats, on the one hand, and yet providing a sufficient flexibility in one direction for use in connection with guide grooves or channels having sharply curved portions or corners, on the other hand.

For practical purposes, the width w of the grooves 11a and 11b, as well as of the locking or claw portions 12a and 12b may advantageously be equal to about one-third of the gauge thickness D of the slats, while the depths d of the grooves or depressions 11a and 11b and, in turn, the height h of the claw portions 12a and 12b may advantageously be of the order of from 60% to 65% of said thickness, to provide a closely fitting and yet sufficiently flexible and easily slideable closure unit or structure. In other words, the ends 13a and 13b of the claw portions 12a and 12b extend about 20% to 30% beyond the median line $a-a$. However, these values may be varied to some extent, to suit existing conditions or practical requirements. Furthermore, the width l of the slats may also be varied to comply with existing specifications, such as the degree of curvature of the guide grooves provided for cooperation with the assembled slats. For normal use, such as for rolling doors or covers, a width l equal to about 2 to 2.5 times the thickness D has been found to produce satisfactory results.

There is thus provided by the invention a flexible closure device or structure comprised of a set of slats frictionally engaging each other in the assembled position and being capable of relative pivotal or flexing movement in one direction in cooperation with and upon being inserted or mounted in the cooperating curved guide grooves of a pair of supporting members, substantially without requiring any special or separate connecting or securing means between the adjacent slats of the unit.

As a result, the closure device may be assembled simply and expeditiously by interlocking the straight end portions of one slat with the straight groove of the adjacent slat and by sequentially inserting or feeding a desired number of slats into the guide grooves or channels of the supporting unit or device. In a similar manner, the device may be disassembled instantly, to remove or replace any defective parts or elements and/or for the purpose of carrying out repairs or adjustments.

The practical uses and applications of the closure device according to the present invention are numerous, as will be understood. Suffice it to mention only its use as a sliding or rolling door, as a cover for desks, cabinets, furniture, etc. or in general, for any type of container or receptacle, the use as a shutter, as well as for many other applications or uses in practice.

In the foregoing the invention has been described with reference to a specific illustrative device. It will be evident, however, that variations and modifications, as well as the substitution of equivalent elements for those shown herein for illustration, may be made in accordance with the broader purview and scope of the invention as set forth in the appended claim.

I claim:

A device of the character described comprising a support having a pair of parallel passageways including at least one straight portion and one curved portion in respect to the plane of said straight portion, and a flexible closure structure slideable within said passageways being constituted by a plurality of mutually interengagable slats each having a flat rectangular cross-section and formed with claw-shaped end portions at the opposite longer edges thereof, said end portions having a height less than the thickness of the slats and being formed by a pair of substantially straight-walled grooves having a width equal to about one third of the thickness of said slats and a depth of about 60 to 65% of said thickness and being parallel to and spaced from said edges and extending from opposite faces of the slats, the inner lateral wall of one of said grooves and the outer lateral wall of the other groove being substantially normal to said faces and the width and depth of said grooves being equal, respectively, to the width and height of said end portions, whereby, with the end portions of one slat being interlocked with the grooves of the adjacent slats, the slats being positioned with their short edges engaging the straight portion of said passageways form a closely fitting structure being aligned at right angles to said passageways and presenting a substantially continuous plane surface, the inner surface of the groove adjacent to one of said longer edges and the outer surface of the end portion at the opposite short edge of the slats slanting inwardly in respect to a central symmetry line transverse to the slats, whereby to enable a relative pivoting movement of adjacent slats in one direction, to conform with the curved portion of said passageways during passage therethrough of said structure.
